[57] CLAIM

The ornamental design for a set of gas tubes for gas barbecue grills, as shown and described.

DESCRIPTION

FIG. 1 is a perspective view of a set of gas tubes for gas barbecue grills to one another, showing my new design; FIG. 2 is a front elevational view thereof; FIG. 3 is a right side elevational view thereof; FIG. 4 is a left side elevational view thereof; FIG. 5 is a rear elevational view thereof; FIG. 6 is a top plan view thereof; and, FIG. 7 is a bottom plan view thereof.

The burner shown in broken lines in all views is for illustrative purposes only and forms no part of the claimed design.
